LIQUID FEED SYSTEM

Original Filed April 26, 1920 2 Sheets-Sheet 2

UNITED STATES PATENT OFFICE.

ERNEST R. HUNTLEY, OF TOLEDO, OHIO, ASSIGNOR TO INDUSTRIAL RESEARCH CORPORATION, OF TOLEDO, OHIO, A CORPORATION OF DELAWARE.

LIQUID-FEED SYSTEM.

Application filed April 26, 1920, Serial No. 376,437. Renewed August 3, 1922. Serial No. 579,473.

To all whom it may concern:

Be it known that I, ERNEST R. HUNTLEY, a citizen of the United States, residing at Toledo, in the county of Lucas and State of Ohio, have invented certain new and useful Improvements in Liquid-Feed Systems, of which I declare the following to be a full, clear, and exact description.

This invention relates to improvements 10 in liquid feed systems, and consists primarily in means for raising liquid from a low level tank to a high level receptacle by suction which is relieved intermittently to prevent the fluid from being drawn into 15 the suction pump. The invention consists also in means for automatically cutting off the suction to stop the pumping action whenever the use of liquid falls below the 20 quantity capable of being furnished by the pump.

The principal object of the invention is the provision of means for accomplishing the above results by comparatively simple and inexpensive apparatus of a character 25 not like to get out of order.

A further object of the invention is the provision of a fuel pumping means, in which the pump is located in the same casing with an oil pump, the two pumps being driven 30 from the engine by a single cam or other equivalent means.

Other objects, and objects relating to details of construction and economies of manufacture will appear as I proceed with 35 the description of that embodiment of the invention, which, for the purposes of the present application, I have illustrated in the accompanying drawings, in which:

Figure I is a more or less diagrammatic 40 view showing in elevation an automobile engine and fuel tank with my invention applied thereto.

Fig. II is a central, vertical, sectional 45 view through a double piston pump which may be employed in my invention.

Fig. III is a vertical transverse section taken substantially on the line III—III, Fig. II.

Fig. IV is a central, vertical, sectional 50 view through a high level receptacle and pumping chamber.

Similar reference characters refer to like parts throughout the views.

Referring to the drawings, 10 indicates an internal combustion engine having a

crank case 11 and a carbureter 12. 13 is a fuel tank shown in approximately the position which the main fuel tank ordinarily occupies with relation to the engine in common automobile practice.

The casting, in which is located the two piston pump employed in my invention, may be mounted upon the crank case 11 by means of machine screws 14 and may have a tubular portion 15 projecting through the casing. The casting, including the tubular portion 15, is cored out to form a slide-way for a plunger 16 mounted upon the end of a rod 17, the plunger to be moved in one direction by a cam 18, or the like, driven by the engine. The motion in the opposite direction is produced by a coil spring 19 which bears at one end against the plunger 16 and at the opposite end against the extremity of the cored out portion.

The forward end of the casting is merely a shell for a chamber 20 open to the atmosphere through a port 21. Opening backwardly out of this chamber in vertical alignment with and upon opposite sides of the rod 17 and the cored out portion 9, are an oil cylinder 22 and an air cylinder 23. In the former slides a disk 24 which has a forwardly extending rod 24'. A hollow piston 25 slides in cylinder 23. The head of piston 25 is provided with a port 26 adapted to be covered by a flat check valve 27 held to its seat during the suction stroke of the piston by the action of a coil spring 28, as well as by air pressure. Piston 25 is fixed upon a rod 29 through which is a central bore 30 acting as an air passage for the discharge of air from the cylinder during the inward stroke of the piston. The cylinder 23 is provided with a port 8 for the admission of air at the end of the suction stroke. Rods 24' and 29 are connected at their outer extremities by a yoke 31 through the center of which the rod 17 extends and to which it is secured by a nut 32 or other suitable means.

At its rear end the cylinder 22 is in communication upon opposite sides with valve chambers 33 and 34 containing ball checks 35 and 36 respectively. The ball 35 is pressed towards its seat by a comparatively heavy spring 37, while the ball 36 is pressed towards its seat by a somewhat lighter spring 38. Nipples 39 and 40 are secured in the casting opposite the cham-

bers 33 and 34. These nipples are threaded to receive clamping nuts 41 which retain in position pipes 42 and 43 for conducting lubricant to certain parts of the engine 5 where its presence is essential. Extending downwardly from the rear end of the cylinder 22 is a valve chamber 44 containing a ball check 45 seating by gravity in the upper end of the bore of a nipple 46, by means 10 of which a pipe 47 is secured to the casting. The lower end of this pipe communicates with an oil reservoir in the bottom of the crank case.

The air cylinder 23 is connected at its 15 rear end by means of a nipple 50 and clamping nut 51 to the pipe 52 which leads to the upper end of a float chamber 53. The latter includes a top 54 which has a central upwardly extending nipple to take a clamping 20 nut 55, holding the pipe 52 in place and forming a tight joint therewith. The lower end of the bore of this nipple constitutes a valve seat into which fits a conical valve piece 56, having a stem 57 guided near its 25 lower end in a perforated plate 58. A float 59 mounted upon the stem 57 is adapted to raise the valve piece to shut off communication with the pipe 52 whenever the liquid in the float chamber reaches a predetermined 30 level.

The bowl 60 of the float chamber is extended into a member 61 roughly tubular in shape, the interior of which is in communication with the float chamber through the 35 perforations in plate 58. The member 61 has a tubular arm 62 extending upwardly at an inclination. A flat check valve 63 is mounted upon the end of this arm to close by gravity, the valve being pivoted, guided, 40 and at the same time held from too great movement by a doubly bent wire 64 fixed in the arm 62 upon opposite sides of the opening therethrough. To the lower end of the member 61 is threaded a nipple 65 which 45 contains a valve chamber 66 in which there is located a flat upwardly opening check valve 67. The chamber and passages located within the valve 56, 63 and 67 together make up what I call my pumping chamber. 50 A clamping nut 68 threaded onto the nipple 65 forms a union with the upper extremity of a pipe 69 leading back to the main tank 63 and extending downwardly through the top thereof to a position near the bottom 55 of the tank.

The pumping chamber delivers fluid through valve 63 into the high level receptacle. In the embodiment illustrated, this high level receptacle takes the form of an 60 auxiliary tank 70, fixed upon and surrounding the pumping chamber. However, I wish to have it understood that this arrangement is merely a preferred embodiment, rather than an essential form of apparatus, as it 65 will be perfectly obvious that the auxiliary

tank might be omitted and the fuel delivered directly from the pumping chamber into the float chamber of the carburetor. In that event the carburetor itself would be the high level receptacle hereinafter referred to. 70

In the top of the auxiliary tank 70 I make a small port 71 for the admission of air, in order that the pressure within this tank may be atmospheric. A pipe 72 is connected with the bottom of the tank by means of a nipple 73 and clamping nut 74 and empties into carburetor 12, which is mounted upon the engine at a level lower than the tank 70 in order that it may be fed by gravity from that tank. 75

Operation.

The plunger 16 and rod 17 reciprocate at a speed proportional to the speed of the engine. As will be obvious, upon the suction stroke of piston 24 oil is drawn into the cylinder 22 from the reservoir in the bottom of the crank case through pipe 47 and nipple 46 past ball check 45 and through valve chamber 44. Upon the compression stroke 90 of the piston this charge of oil is forced past ball checks 35 and 36 through valve chambers 33 and 34 and nipples 39 and 40 out through pipes 42 and 43 to the parts of the engine in need of lubrication. It is assumed that more lubrication is needed by the parts served by pipe 43 than those served by pipe 42, and to this end the spring 38 is made of lighter wire than spring 37, thus enabling the pump pressure to unseat ball check 33 for a longer time than ball check 35. After the oil flows through the bearings 95 to be lubricated, it flows back again by gravity to the bottom of the crank case. Thus it is kept in circulation. 100

The raising of fuel is accomplished by the production intermittently of a partial vacuum in the pumping chamber, the pressure in the pumping chamber being substantially atmospheric in the intervals between the suction impulses. The suction pump operates at a speed proportional to the speed of the engine, but fuel is raised in amounts sufficient only to meet the requirements of the engine, the action of the pumping chamber being automatically controlled. During each outward or forward stroke of piston 25 the air contained in the top of the pumping chamber and in the pipe 52 is partially exhausted. This enables atmospheric pressure on the top of the fuel in the main tank to force fuel out through pipe 59 past check valve 67 into the pumping chamber, the check valve 63 remaining closed. As soon as the port is uncovered by the piston in its forward motion air rushes into the cylinder 23 and thence through pipe 52 to the top of the pumping chamber, and the pressure thus conveyed to the top of the liquid in that chamber closes check valves 67 and opens 115 120 125 130

check valve 63 permitting a certain amount of fuel to be discharged through the latter valve into the high level receptacle, which in the present instance, is the auxiliary tank 5 70. Upon the inward stroke of the piston 25 the check 27 opens permitting passage of air through port 26 in the piston head and through passage 30 in the rod 29, thus tending to equalize the pressure on both sides of 10 the piston. Fuel as required by the carbureter in the meantime flows through pipe 72 to the carbureter bowl. The apparatus is so designed, however, as to be capable of furnishing fuel in excess of the needs of the 15 carbureter. Hence, the auxiliary tank 70 soon fills. Fuel in the float chamber 53 probably stands at approximately the same level as that in the tank 70. When this level rises sufficiently, the float 59 raises the valve 20 56 and interrupts communication between the pumping chamber and the pipe 52. The next suction stroke of the piston 25 merely creates a partial vacuum in the pipe 52 which is relieved at the end of the stroke by air entering through port 8. This action continues until the fuel drawn off by the carbureter permits the float 59 to descend and open the valve 56 when the pumping action 25 is automatically resumed.

30 Certain features of my invention disclosed but not claimed herein are disclosed and claimed in my copending application Serial No. 372,046, filed April 7, 1920 for Vacuum feed systems to which application cross reference is hereby made.

I am aware that the particular embodiment of my invention above described, and illustrated in the accompanying drawings, is susceptible of considerable variation without departing from the spirit thereof, and therefore I desire to claim my invention broadly as well as specifically as indicated by the appended claims.

I claim as my invention:

45 1. In a liquid feed system, means for producing suction impulses intermittently and for restoring approximately atmospheric pressure in the intervals between the suction impulses, a low level main liquid tank, a 50 high level receptacle, a pumping chamber in communication with said tank and with said receptacle, a connection between said first named means and the top of said pumping chamber, a float in said pumping chamber and a valve controlled by said float 55 adapted to close said connection.

2. In a liquid feed system, means for pro-

ducing suction impulses intermittently and for restoring approximately atmospheric pressure in the intervals between the suction impulses, a low level main liquid tank, a high level receptacle, a pumping chamber in communication with said tank, a connection between said receptacle and chamber through which fluid may flow by gravity from the chamber to the receptacle, a connection between said first named means and the top of said pumping chamber, a float in said pumping chamber and a valve controlled by said float adapted to close said connection.

3. In a liquid feed system, a main low level tank, a high level receptacle, a pumping chamber mounted within said receptacle and in communication therewith through a check valve, a connection between said pumping chamber and said main tank, a check valve adapted to close said connection, means for producing suction impulses intermittently and for restoring approximately atmospheric pressure in the intervals between the suction impulses, a connection between said means and the upper part of said pumping chamber, a float in said pumping chamber and a valve controlled by said float adapted to close said last named connection.

4. In a liquid feed system, means for producing intermittent suction impulses and for restoring approximately atmospheric pressure in the intervals between the suction impulses; a low level main liquid tank, a high level receptacle, a pumping chamber in communication with said tank and said receptacle, and a connection between the suction producing means and the top of said pumping chamber.

5. In a pump system for engines, the combination of a pump casing, a pump chamber connected with said casing, means in said casing for producing suction impulses in said chamber, means for restoring the pressure in said pump chamber to that of the atmosphere in the intervals between the suction impulses.

6. In a pump system, the combination of a pump casing, plural reciprocating members within said casing, said members reciprocating along parallel axes, and single means for operating said members, one of said reciprocating members being provided with pressure relieving mechanism.

In testimony whereof, I affix my signature
ERNEST R. HUNTLEY.
